[57] CLAIM

The ornamental design for a combined apertured board
and storage elements therefor, substantially as shown.

DESCRIPTION

FIG. 1 is a front perspective view of the combined
apertured board and storage elements therefor showing
our new design;

FIG. 2 is a front elevational view;

FIG. 3 is a top plan view;

FIG. 4 is a bottom plan view;
FIG. 5 is a side elevational view taken from the right of
FIG. 1, the side opposite being a mirror image thereof;
FIG. 6 is a back elevational view.
